US0D1087996S

(12) **United States Design Patent** (10) **Patent No.:** **US D1,087,996 S**
Sanborn et al. (45) **Date of Patent:** **** Aug. 12, 2025**

(54) **DISPLAY SCREEN OR PORTION THEREOF WITH A GAMING MACHINE GRAPHICAL USER INTERFACE**

(71) Applicant: **Aristocrat Technologies, Inc.**, Las Vegas, NV (US)

(72) Inventors: **Hanna Sanborn**, Georgetown, TX (US); **Chad La Guardia**, Austin, TX (US); **Erick Ching**, Cedar Park, TX (US); **Rogelio Decasa, Jr.**, Renton, WA (US)

(73) Assignee: **Aristocrat Technologies, Inc.**, Las Vegas, NV (US)

(**) Term: **15 Years**

(21) Appl. No.: **29/910,290**

(22) Filed: **Aug. 17, 2023**

(57) **CLAIM**

The ornamental design for a display screen or portion thereof with a gaming machine graphical user interface, as shown and described.

DESCRIPTION

FIG. 1 is a front view of a display screen or portion thereof with a gaming machine graphical user interface showing a first embodiment of our new design;

FIG. 2 is a front view of a display screen or portion thereof with a gaming machine graphical user interface showing a second embodiment of our new design;

FIG. 3 is a front view of a display screen or portion thereof with a gaming machine graphical user interface showing a third embodiment of our new design; and,

FIG. 4 is a front view of a display screen or portion thereof with a gaming machine graphical user interface showing a fourth embodiment of our new design.

The outer dash-dash-long dash line shows a display screen or portion thereof that forms no part of the claimed design. The dashed broken lines show portions of the graphical user interface and form no part of the claimed design.

1 Claim, 4 Drawing Sheets
